(57) **CLAIM**

The ornamental design for an air chute, as shown and described.

DESCRIPTION

FIGS. 1A and 1B are a top perspective view of an air chute showing our new design;

FIGS. 2A and 2B are a top view thereof;

FIGS. 3A and 3B are a bottom view thereof;

FIGS. 4A and 4B are a front, side view thereof, and a rear view (not shown) is a mirror image of FIGS. 4A and 4B;

FIG. 5 is a left side view thereof;

FIG. 6 is a right side view thereof; and,

FIG. 7 is an enlarged view of the circled area shown in FIG. 1B.

Surface shading in the FIGS. 1-7 is provided to show clearly the character and contour of all surfaces of any three-dimensional aspects of the design. The broken lines shown in the drawings are for illustrative purposes only and form no part of the claim design.
